UNITED STATES PATENT OFFICE.

JOSEPH BERCHA, OF BEATRICE, NEBRASKA.

GRINDING-MILL.

942,768.

Specification of Letters Patent. Patented Dec. 7, 1909.

Application filed May 4, 1909. Serial No. 493,860.

To all whom it may concern:

Be it known that I, JOSEPH BERCHA, a citizen of the United States, residing at Beatrice, in the county of Gage and State of Nebraska, have invented new and useful Improvements in Grinding-Mills, of which the following is a specification.

This invention relates to improvements in machines for crushing and grinding grain, the main object of the invention being to provide a construction of machine whereby the rapid and effective grinding of grain may be effected without clogging or heating of the grain during the process of grinding, to provide means for grinding either coarse or fine grain to a suitable degree of fineness, and to mount the grinding elements in such manner as to permit of their ready adjustment for a fine or coarse action, to prevent their injury by excess adjustment or the passage of foreign particles through the machine, and to provide for the ready removal and replacement of worn out parts without the removal of parts which are still good for service.

A further object of the invention is to provide a construction of grinding mechanism by which two or more different kinds of grain may be ground simultaneously without admixture thereof, and to provide a crushing attachment for the mill by which ear or head corn and bulky or unshelled grains may be reduced to a suitably comminuted condition prior to grinding, such attachment being susceptible of removal from the machine when its use is not required.

With these and other objects in view, the invention consists of the features of construction, combination and arrangement of parts hereinafter fully described and claimed, reference being had to the accompanying drawings, in which:

Figure 1 is a vertical section through the machine taken on the line of the operating shafts. Fig. 2 is a similar section taken at right angles to the plane of section of Fig. 1. Fig. 3 is a perspective view of the hanger arm and the concave sections supported thereby, the latter being removed therefrom. Fig. 4 is a perspective view of the coacting grinding roll.

Referring to the drawings, 1 designates the frame of the machine, on which is sup-

ported a casing 2 divided by a central vertical partition 3 into counterpart vertical chambers or compartments 4 and 5 open at their upper ends for the feed of the grain thereto, and each provided with an outwardly and downwardly curved lower end 6 terminating in a discharge spout or outlet 6 for the ground grain.

Arranged vertically within the rear of each chamber or compartment is a bracket or hanger arm 7 having an outwardly curved end 8 and provided at its upper end with a hooked portion 9 which projects outwardly through a slot 10 in the upper rear wall of the casing and forms a guide engaging said wall. To the outer or depending portion 70 of this hook is pivotally mounted at its upper end an adjusting screw 11 passing downwardly through an opening in a guide lug 12 and provided above and below the same with hand nuts 13 and 14 by which 75 said screw may be respectively raised and lowered to correspondingly adjust the bracket arm.

The lower curved end of the bracket arm is formed with a concaved seat 15 separated into upper and lower portions by a transverse recess 16 and having at its lower end a transverse bearing or stop shoulder 17. This seat is adapted to receive and support a grinding concave composed of upper and lower sections 18 and 19, the upper section being adapted to occupy the upper portion of the seat and bear against a shoulder 20 at the upper end thereof, while the lower section 18 is adapted to occupy the lower portion of the seat between the lower edge of said upper section and the shoulder 17. The section 19 is clamped in position by the section 18, which latter is formed on its under side with a transverse rib 21 to fit within the recess 16 and is provided with a countersunk opening 22 for the passage of a screw or rivet 23, which is also adapted to pass through an opening 24 in the bracket arm to secure said upper concave section in position.

A drive shaft 25 extends through openings in the partition and side walls of the compartments and is journaled in suitable bearings 26 provided upon said walls. One 105 end of this shaft carries a fly wheel pulley 27 by which the motion of the shaft is balanced and to which power may be communica-

cated from a drive belt leading from a suitable motor. Mounted on this shaft within each compartment is a grinding roll or bur 28 arranged opposite the concave in the 5 throat or passage between the lower end of the compartment and its discharge spout 6 and properly disposed with reference to the concave for the passage between them of the grain to be ground. The acting surfaces of 10 the concave sections and the periphery of the roll are provided with grinding faces of zigzag construction, such as disclosed in the patent to Bercha and Chapman, #689,034, dated December 17, 1901 in order to prevent 15 undue spreading of the grain and clogging and heating of the grain during the grinding action.

The concave is adjustable with relation to the bur both vertically and radially in order 20 to regulate the size of the intervening grain passage and to dispose the grinding surfaces in proper relation for a coarse, fine or intermediate grinding action. The vertical adjustment is effected by means of the screw 25 11 and hand nuts 13 and 14, by which the distance between the grinding surfaces may be regulated in an obvious manner. In order to limit the downward vertical adjustment of the concave an angular stop bracket 30 27 is detachably and adjustably secured to the lower wall of the outlet 6 by a screw 30, which screw passes through a slot 31 in said plate, and an angular washer 32 is clamped by the head of the screw against the body 35 of the bracket and bears against the upturned flange thereof to prevent independent pivotal movement of said bracket. The upward vertical adjustment of the concave is limited by an adjustable stop screw 33 40 mounted upon a detachable chamber 34 secured upon the top of the casing by bolts 35, the bracket and screw serving to limit the adjustment of the concave in either direction beyond predetermined degrees so as 45 to prevent possible contact between and injury to the grinding surfaces. The bracket arm is pivotally supported in the manner described for a yielding movement of the concave toward and from the bur, and this 50 yielding movement is cushioned and limited by a coiled spring 36 extending through an opening in a boss 37, said opening having its outer end internally threaded to receive a screw plug 38 by which the pressure of the 55 spring may be regulated. This spring allows the concave to yield outwardly from the bur when a nut, nail or other hard foreign object mingled with the grain is encountered, thus preventing the grinding 60 surfaces of the roll and concave from being injured thereby, as well as to cushion and take up all shocks and jars from the sudden backward movement of the concave under such conditions.

Arranged above and in parallel relation with the shaft 25 is a countershaft 39 which extends through openings in the partition and sides of the compartments and is journaled in suitable bearings 40 and provided at one end with an internal gear 41 meshing with a pinion 42 on the end of the shaft 25 opposite the pulley 27, by which said countershaft is driven from the drive shaft. Keyed upon the countershaft within each chamber or compartment is a rotary force 70 feed device 43 provided with toothed arms 44 at diametrically opposite sides thereof to engage and force the grain down to the concave and grinding roll, by which the material is fed to the grinding devices in an effective manner and banking of the same 80 above the roll prevented. Within the upper portion of each compartment is mounted a sliding valve or plate 45 to control the feed of grain thereto, said plate being movable 85 outwardly through a slot 46 in the front wall of the compartment and held in adjusted position by a set screw 47.

The detachable top casing 34 supports contained means for preliminarily grinding 90 ear or head corn or other bulky and unshelled grains too large or coarse to be ground without reduction between the grinding roll and concave. This casing is adapted to receive and support a sheet metal hopper 48 into which the material to be crushed and ground is introduced. Secured by bolts or otherwise to the front and rear walls of the casing 34 are opposite sets of stationary crushing devices 49 and 50, the one having 100 a concave and the other a convex body portion or surface, and provided respectively with sets of spaced ribs 51 and 52 against and between which the material is crushed by the action of a crushing roll hereinafter 105 described. The lower end of the crushing device 49 terminates in a bar 53 extending across the outlet at the lower end of the casing 34 to divide the discharging crushed material into two streams for feed into the 110 grinder casing 2, by which the material is prevented from choking in said outlet, and between this bar and the concaved body of the device 49 slots 54 are also formed for the downward feed of the crushed material. 115

The side walls of the casing 34 are provided with bearings 55 for a shaft 56 which is provided at one end with a gear 57 meshing with a gear 58 on the countershaft 39, by which the shaft 56 is driven. On said 120 shaft 56 within the crusher chamber is rigidly mounted a rotating crushing roll 59 provided with annular longitudinal series of crushing teeth or blades 60 arranged for movement in the rotation of the rolls between the crushing flanges of the concaves or breaker plates 49 and 50, by which the corn or other material will be loosened up,

carried downward and crushed or disintegrated between the teeth and flanges and surfaces of said breaker plates.

- In practice, the grinding roll is rotated 5 by the shaft 25 at a desired high rate of speed, while the gearing between said shaft and the countershaft is proportioned to rotate the feeder 44 at about one-third the rate of speed of the grinding roll, while 10 the gears 57 and 58 are proportioned to drive the crushing roll at a still slower rate of speed, so that a proper amount of material may be fed to the grinding roll and an excess feed prevented.
- 15 When it is not desired to use the crushing attachment, this part of the device may be removed by detaching the bolts 35 and the grain may be fed directly into the compartments 4 and 5 or into any suitable type of 20 hopper applied in lieu of the crushing attachment.

It will be manifest from the foregoing description that different kinds of grain may be fed into the compartments and ground 25 simultaneously without admixture, and in practice any desired number of compartments and sets of grinding and coacting feed devices may be employed.

Having thus fully described the invention, 30 what is claimed as new, is:—

1. In a grinding apparatus the combination of a casing having a slot in the upper end thereof, a grinding roll in the lower portion of said casing, a vertical bracket 35 arm having a curved lower end partially surrounding the roll and a projection at its upper end extending exteriorly through said slot, a concave carried by the curved lower end of the arm, an adjustable support on 40 the exterior of the casing to which said projection is pivotally connected, and a spring upon the casing yieldingly backing the curved end of the arm.

2. In a grinding apparatus, the combination of a casing, a grinding roll at the lower 45 end of the casing, a bracket arm extending vertically within the casing having a curved lower end carrying a concave arranged adjacent the roll, a vertically adjustable support pivotally connected with the upper end 50 of the arm, a spring upon the casing and yieldingly backing the curved end of the arm, and an adjustable stop for limiting the upward vertical adjustment of the arm, and 55 an adjustable stop for limiting the downward vertical adjustment of the arm.

3. In a grinding apparatus, the combination of a casing having a slot at the upper 60 end thereof, a grinding roll journaled in said casing, a bracket arm vertically arranged within the casing and having a lower curved end carrying a concave for coaction with the roll and provided at its upper end with a projection extending through

said slot, a screw stem supported exteriorly 65 of the casing and pivotally connected with said projection, adjusting nuts for raising and lowering said stem, and a spring arranged upon the casing and yieldingly backing the curved end of the bracket.

4. In a grinding apparatus, the combination of a casing having a slot in the upper end thereof, a grinding roll within the casing, a vertically disposed bracket arm within the casing having a lower curved end partially surrounding the roll and having a projection at its upper end extending through said slot, a concave carried by the curved end of the arm, an adjustable support upon the exterior of the casing pivotally connected with said projection, a concave carried by the curved end of the arm, adjustable stops engaging the upper and lower ends of the arm for limiting the vertical movements thereof, a spring upon 80 the casing yieldingly backing the curved end of the arm, and means for varying the tension of said spring.

5. In a grinding apparatus, the combination of a casing having a slot therein, a grinding roll within the casing, a vertical bracket arm within the casing having a lower curved end partially surrounding the roll and having a projection at its upper end extending outwardly through said slot, 90 a sectional concave carried by the curved end of the arm, a bracket on the exterior of the casing, a threaded rod carried by the bracket and pivotally connected with said projection, nuts upon said rod above and below the bracket for vertically adjusting the rod, a spring upon the casing yieldingly backing the curved end of the arm, means for regulating the resistance of said spring, and adjustable stops engaging the upper 95 and lower ends of the arm for limiting the vertical movements thereof.

6. In a grinding apparatus, the combination of a casing, a grinding roll journaled horizontally therein, a vertically arranged bracket arm having a curved lower end partially surrounding the roll and provided with a grooved seat, a concave composed of sections detachably secured in said seat, means for yieldingly backing the curved end 100 of the bracket arm, and means pivotally connecting the upper end of said arm to the casing, said means embodying means for adjusting the arm in a vertical plane.

7. In a grinding apparatus, the combination of a casing, a grinding roll therein, a bracket arm having a grooved lower end, means for pivotally supporting said bracket arm, means for vertically adjusting the same, a concave detachably fitted in the 110 grooved portion of the arm, and means for yieldingly backing the arm.

8. In a grinding apparatus, the combina-

tion of a casing, grinding mechanism there-
in, spaced parallel stationary breaking de-
vices within the casing above said grinding
mechanism, one of said breaking devices
5 having a concaved body portion provided
with spaced breaking flanges and the other
having a convex body portion provided
with oppositely arranged spaced breaking
flanges, and a rotary crusher arranged be-

tween said breaking devices and provided 10
with fingers movable between the flanges
thereof.

In testimony whereof I affix my signature
in presence of two witnesses.
